DESIGN FOR A CHILD'S BIB

Margaret Mann Cameron, New York, N. Y.

Application March 13, 1946, Serial No. 127,443

Term of patent 7 years

(Cl. D3—26)

To all whom it may concern:

Be it known that I, Margaret Mann Cameron, a citizen of the United States, residing at New York city, in the county of New York and State of New York, have invented a new, original, and ornamental Design for a Child's Bib, of which the following is a specification, reference being had to the accompanying drawing, forming a part thereof,

I claim:

The ornamental design for a child's bib, as shown.

MARGARET MANN CAMERON.
